DECORATIVE CENTERPIECE

Walter T. Heintze, Elizabeth, N. J., assignor to
Fostoria Glass Company, Moundsville, W. Va., a
corporation of West Virginia

Application May 27, 1948, Serial No. 29,576

7 Claims. (Cl. 67—23)

1

This invention relates to decorative settings and more particularly to a centerpiece set designed for use on a buffet, side table, dining table, console table or the like. The invention provides a novel decorative device adapted for the retention of both candles and a floating garden, lily pond, floral display, fruits or other objects.

The invention provides a novel self-contained device which is readily susceptible of countless changes and variations of decorative motif, including both the number and arrangement of candles, floral pieces or other articles.

Heretofore it has been customary to use separate candlesticks with an epergne or other independent article or articles such as, for example, bowls of flowers. Many of such items are costly and do not readily lend themselves to adaptation with the candlesticks.

An object of the present invention is to provide a centerpiece of the character described as a self-contained and complete unit, possessing a maximum degree of flexibility in order to encourage expression and the personality of the individual user.

Another object of the invention is to provide a decorative centerpiece which may be used independently or with table settings.

A further object of the invention is to provide a centerpiece of the character described having separable candle supporting members so that any desired number and arrangement of such supporting members may be utilized within the numerical limitations of the device.

A further object of the invention is to provide a decorative centerpiece which may be economically manufactured and sold and which will combine aesthetic beauty with simplicity of design.

Further objects and advantages of the invention will be apparent from the following specification taken in conjunction with the accompanying drawings, wherein:

Fig. 1 is a top plan view illustrating a preferred embodiment of the invention;

Fig. 2, a central vertical sectional view through the complete unit with a portion of the candlestick supporting element and one of the candle supports illustrated in elevation; and

Fig. 3, a bottom plan view of one of the candle holding or supporting elements.

With continued reference to the drawings the present invention comprises an attractive artistic centerpiece including a relatively shallow bowl 10 having a depression or concavity 11 in its upper surface and an annular shoulder 12 around the same for retaining a center block 13 at the

desired location within the bowl 10. The rim of the bowl may be fluted or have any other desired ornamental configuration.

The center block may have a configuration generally similar to that of the rim of the bowl, thus providing a matched pleasingly aesthetic appearance. This similarity of shape in the present instance is accomplished by making the block of six segments 14 corresponding to the six flutes of the bowl. The block is provided with spaced sockets 15 of teardrop or noncircular cross-section spaced about a central candle socket 16. Each teardrop socket is pointed toward the central candle socket and is adapted to receive a corresponding teardrop cross-section forming the lower end 17 of a candle support 18 having a candle socket 19 on its upper end with a curved decorative extremity 20. In other words the candle support 18 has its ends offset with its upper end carrying a candle socket and its lower end having a teardrop cross-section to fit into one of the teardrop sockets in the center block. The cooperating teardrop sockets and teardrop extremities of the candle supports cooperate to prevent free rotation of the candle support in the center block and with respect to the center block and permit the selective use of from one to six of the candle supports in any desired arrangement. This structure likewise permits ready application or removal of each candle socket and prevents rotation thereof.

It will be noted that the center block has a larger recess 21 above and encompassing the socket 16 and all of the sockets 15 and that the candle supporting members 17 with their upper ends apart, incline outwardly and rest against the vertical shoulder or wall formed in the block by the said recess 21.

In Fig. 1 of the drawing, two candle supports 40 are illustrated in opposed relationship. Obviously, two more supports may be used with the center block illustrated, or any number of such candle supports up to six may be employed. It also will be readily apparent that when any lesser number are utilized, the spacing will be greater and the use of a candle in the central socket likewise is entirely optional and is not dependent upon the number or arrangement of candle supports.

It will be obvious to those skilled in this art that the ramifications of decorative possibilities with the present device are virtually limitless as to the contents of the bowl and that candle arrangement is restricted only by the size of the

center block and the number of sockets provided therein.

Further, various changes may be made in the invention without departing from the spirit and scope thereof and therefore the invention is not limited by that which is shown in the drawing and described in the specification, but only as is indicated in the appended claims.

What is claimed is:

1. A centerpiece comprising a complete unit including a relatively shallow bowl for receiving and holding in a dry state or in a bath one or more objects of a decorative character appropriate for contributing to a desired attractive effect, said bowl having an elevated central portion with a concavity in its upper surface, a center block composed of a series of sections having curved outer faces and located in said concavity, said center block having a central candle-receiving socket and sockets of teardrop cross-section spaced therearound, candle-supporting means having candle holders supported on the upper ends thereof and having lower extremities of teardrop configuration in cross-section for complementary reception in said sockets of teardrop cross-section, said candle-supporting means being curved between extremities and when in position of use have its intermediate portion bear upon the upper portion of a pair of adjacent sections of said center block.

2. A centerpiece comprising a complete unit including a relatively shallow bowl for receiving and holding in a dry state or in a bath one or more objects of a decorative character appropriate for contributing to a desired attractive effect, said bowl having a central portion with a concavity in its upper surface, a center block located in said concavity with a central candle-receiving socket and sockets of teardrop cross-section spaced therearound, candle-supporting means having candle holders supported on the upper ends thereof and having lower extremities of teardrop configuration in cross-section for complementary reception in said sockets of teardrop cross-section, said candle-supporting means being curved between extremities and when in position of use have its intermediate portion bear upon the upper portion of a pair of adjacent sections of said center block.

3. A centerpiece comprising a unit including a bowl for receiving and holding in a dry state or in a bath one or more objects of a decorative character appropriate for contributing to a desired attractive effect, said bowl having a concavity in its upper surface, a center block located in said concavity and provided with a candle-receiving socket and spaced sockets of non-circular cross-section, candle-supporting means having lower extremities of non-circular configuration in cross-section for complementary reception in said sockets of non-circular cross-section, said candle-supporting means having a curved surface between extremities and when in position of use have such curved portion bear upon the upper portion of said center block.

4. A centerpiece comprising a complete unit including a bowl for receiving and holding in a dry state or in a bath one or more objects of a decorative character appropriate for contributing to a desired attractive effect, a raised central portion, a center block composed of a series of sections located in said bowl and provided with

a central candle-receiving socket and sockets of teardrop cross-section spaced therearound, candle-supporting means having candle holders supported on the upper ends thereof and having lower end portions of teardrop configuration for reception against rotation in said sockets of teardrop cross-section, said candle-supporting means when in position of use having its intermediate portion additionally supported by said center block.

5. A centerpiece comprising a block composed of a series of sections having curved outer faces and provided with a central candle-receiving socket and a plurality of sockets for candle-holders spaced therearound, the sockets for the candle-holder being non-circular in cross-section and corresponding in number to the number of said curved faces located adjacent the joint between faces, candle-holders for location in said sockets and having lower ends of non-circular cross-section whereby said candle-holders will be held against rotation, said candle-holders having their upper portions axially offset relative to their lower ends so that when in operative position their intermediate portions may rest against a portion of the center block spaced upwardly from the sockets for said candle holders.

6. A centerpiece comprising a block provided with a central candle-receiving socket and a plurality of sockets for candle-holders spaced therearound, the sockets for the candle-holder being non-circular in cross-section, candle-holders for location in said sockets and having lower extremities of non-circular cross-section whereby said candle-holders will be held against rotation, said candle-holders having their upper portions axially offset relative to the center of said center block from their lower ends so that when in operative position their intermediate portions may rest against the center block in a position upwardly of the sockets for said candle-holders.

7. A centerpiece comprising a relatively shallow container adapted to receive and retain in a dry state or in a bath one or more objects of an ornamental character appropriate to the desired decorative effect, said container being provided with a raised central portion having a depression therein with an annular shoulder surrounding the same, a center block designed to seat in said depression and retained therein by the said annular shoulder, a recess in said center block, a central candle receiving socket within said recess, a plurality of spaced teardrop sockets disposed within the recess about said central candle receiving socket, outwardly curved candle supports having teardrop lower extremities for complementary reception in said teardrop sockets and adapted to rest against the side of said recess, and candle holders supported on the upper ends of said candle supports.
